CHECKER AND CHESSBOARD

David Aiuppa, W207 S8286 Hillendale Drive,
Muskego, Wis. 53150

Original design application Aug. 16, 1971, Ser. No.
172,368, now Patent No. 226,321. Divided and this
application Sept. 5, 1972, Ser. No. 286,493

Term of patent 14 years

Int. Cl. D21—01
U.S. Cl. D34—5 SS

FIG. 1 is a top plan view of the checker and chessboard showing my new design, the opposite side of the checker and chessboard is plain;

FIG. 2 is an end view of the checker and chessboard shown.

This is a divisional of application Ser. No. 172,368, filed Aug. 16, 1971, now design Pat. 226,321.

I claim:

The ornamental design for a checker and chessboard, as shown and described.
